[57] CLAIM

The ornamental design for an in-line transparent drip-
per valve, as shown.

DESCRIPTION

FIG. 1 is a perspective view showing the top, front and
right side of an in-line transparent dripper valve show-
ing my invention.

FIG. 2 is a front elevational view thereof.

FIG. 3 is a right side elevational view thereof.

FIG. 4 is a left side elevational view thereof.

FIG. 5 is a top plan view thereof.

FIG. 6 is a bottom plan view thereof.
